UNITED STATES PATENT OFFICE.

JOSEPH ARTHUR JEFFERY AND BENJAMIN ALFRED JEFFERY, OF NEWARK, NEW JERSEY.

SPARK-PLUG.

1,214,471.

Specification of Letters Patent. Patented Jan. 30, 1917.

Application filed September 23, 1908, Serial No. 454,401. Renewed July 10, 1916. Serial No. 108,451.

To all whom it may concern:

Be it known that we, JOSEPH A. JEFFERY and BENJAMIN A. JEFFERY, of Newark, in the county of Essex, State of New Jersey, have invented certain new and useful Improvements in Spark-Plugs, of which the following is a specification.

This invention relates to certain new and useful improvements in spark plugs.

10 The invention has for its object the production of a simple, inexpensive and highly efficient device of this character in which the conductor or terminal wire is firmly embedded in the insulating body or block in 15 such manner as to provide an absolutely gas-tight union with said insulating body without the use of cement, or the like.

It has been found that an air gap greatly increases the efficiency of a spark plug by 20 introducing sufficient resistance in the secondary circuit to maintain the potential of the latter when accumulations on the surface of the insulating block would tend to reduce the resistance in the circuit. The 25 objection to this air gap is the fact that the resistance is varied by the formation of metallic vapor during the passage of the current; and also the difficulty of sealing the gap so as to prevent oil or other foreign 30 matter from reaching it and either lowering or raising the resistance.

It is one of the objects of the present invention to provide a resistance that will prevent the formation of an arc and which, 35 as a result, will not be materially affected by any matter that may come in contact with it.

40 A further object is to provide an improved binding post, and simple and efficient means for securing the same in position.

45 A further object is to provide improved means for establishing a gas-tight joint between the insulating block and its supporting bushing.

The invention will be hereinafter fully set forth and particularly pointed out in the claims.

50 In the accompanying drawing:—Figure 1 is a longitudinal sectional view illustrating one embodiment of our improved spark plug. Fig. 2 is a similar view of a slight modification thereof. Fig. 3 is a sectional view of an additional modification. Fig. 4 55 is a detail perspective view of the binding

post. Fig. 5 is a view of the securing cap therefor. Fig. 6 is a sectional view of the binding post.

Referring to the drawing, 10 designates the insulating block provided with a longitudinal bore 11 leading in from one end, the other end being closed or made solid, as indicated at 12. The end provided with the bore is tapered at 13 and provided with an annular rib 14, the other end of said block being provided with a head 15. The terminal wire 16 is embedded at its upper end in the closed portion 12 of the block 10, the lower end of said wire extending through bore 11 and protruding from the latter. 70 The rib 14 is engaged by a cup-like ring 17, the portion of said ring extended above said rib 14 being filled with any suitable or preferred packing 18. The rounded portion of ring 17 forms a shoulder which is adapted to rest upon a complementary internal shoulder 19 formed in the usual supporting bushing 20, and the block 10 is rigidly held in position by means of a second bushing 21 75 engaging the inner wall of bushing 20 and provided with a reduced edge 22 arranged to fit within ring 17 and compress the packing 18. In this manner the block 10 is adjustably supported in the bushing 20, the ring 17 providing a bearing that will permit 80 a limited adjustment of the block by a rocking movement thereof before bushing 21 is screwed home. In this connection it will be noted that a decided advantage is gained 85 by reason of the fact that the packing 18 and ring 17 become practically a part of the insulating block, and these parts are all held together when the plug is separated for 90 cleaning or other purposes. In fact it has been found in practice that after the plug 95 has been in use a short time the bushing 21 adheres to the packing 18 and block 10 so strongly that when said bushing is removed it carries with it the insulating block and all 100 of its adjuncts. The ground terminal is formed by a suitable wire 23 secured to bushing 20.

The binding post 24 is provided with a threaded shank and a head 25, the latter being slightly cupped on its underside as indicated at 26, and provided with an external angular portion 27. In the drawing we have illustrated the angular portion 27 as square, but it will be understood that we do not desire to limit ourselves to any particular 105 110 115

shape. The binding post is secured in position by means of a cap 23 provided with an angular opening 29 corresponding in shape to the angular portion of head 25 and constructed to receive said angular portion, the lower edge of said cap being turned over the head 15. A binding nut 30 works on the threaded shank of the binding post and is preferably provided with a head 31 to receive any form of terminal clip, if the same should be used. Or, if desired, the terminal may be clamped in the usual way between the nut 30 and cap 28.

In practice it is of decided advantage to provide a gap at some point in the circuit through the spark plug and this has usually been done by providing an air gap. We have found, however, that excellent results are secured by causing the current to pass through a small body of high resistance. We therefore interpose a thin washer or disk 32 of high resistance material between the binding post 24 and wire 16, and within the recess or chamber 26 of the binding post. We have secured excellent results with a disk of carborundum, but do not desire to limit ourselves to any specific material.

In Fig. 2 we have illustrated a slight modification which consists in reducing the diameter of wire 16 near its end, as indicated at 33. In Fig. 3, a like result is attained by interposing an independent conductor 34 between the wire 16 and the end of the block 10.

It is well known in the art that while attempts have been made to bake a conductor wire within an insulating block, such attempts have been without practical success for the reason that the shrinkage of the porcelain in baking is such that the insulation draws away from the wire, thereby destroying the gas tight union that is so necessary in devices of this kind. Another disadvantage encountered in baking in the terminal wire is that the wire anneals under the temperature of the kiln and becomes so softened that it will buckle when the porcelain commences to contract or vitrify, thereby spoiling the shape of the plug and rendering the same useless. We have found that these disadvantages are overcome by using a wire containing nickel and chromium. The surface of this wire during the firing process effects a firm chemical union with the insulator throughout its length, which union is absolutely gas tight. By this means a wire may be used of sufficient diameter to be left above the face of the insulator and at the same time, by reason of its size, resist the disintegrating action of the spark. This alloy also possesses the additional advantage that it will not anneal or soften to any material degree under the temperature developed in the baking process, thereby aiding in holding the block to its proper shape.

The importance of this feature lies in the fact that all porcelains of great heat resisting qualities or those that will resist the extremely rapid changes of temperature must contain a lesser amount of flint, or similar ingredients, such ingredients being added to make the articles fire straight but at the expense of the qualities so desired in an insulator for spark plugs. It will be noted, however, that we do not desire to limit ourselves to the specific alloy mentioned, as good results have also been secured with other metals. A further advantage is gained by arranging the disk of high resistance material in the circuit. It is well known that the ordinary air gap employed for this purpose is usually filled with metal vapor during the electrical discharge, thus in a measure defeating the object of the gap. The high resistance disk prevents the formation of such vapors, and at the same time provides a path of unvarying resistance equal to that of the ordinary spark gap. It will also be noted that in the spark plugs now in general use much trouble is experienced by the loosening and disarrangement of the central electrode and gasket when the nuts, etc., used to fasten the battery terminal to the plug, are tightened down finally. This trouble is eliminated by forming the binding post with the squared head, and bending down the securing cap to engage any depression or protuberance, on the head of the insulating block, that may be there by accident or intent, the said cap being so designed as to have a slight springing effect. Thus in the event of any excessive torsional strain the cap and post may rotate without in any manner impairing the efficiency of the device.

We claim as our invention:—

1. In a spark plug, an insulating block, a conductor carried thereby, an electric terminal carried by said block and in circuit with said conductor, a gap being formed between said terminal and said conductor, and an arc-preventing resistance material in said gap to prevent passage of any currents but those of high potential.

2. In a spark plug, an insulating block, a conductor carried thereby and forming part of the circuit through said plug, a gap being formed in said circuit, and a solid body of arc-preventing high resistance material in said gap to prevent the passage of any currents but those of high potential.

3. In a spark plug, an insulating block, a conductor carried thereby and forming part of the circuit through said plug, a gap being formed in said circuit, and a solid body of carborundum in said gap to prevent the passage of any currents but those of high potential.

4. In a spark plug, an insulating block, a conductor carried thereby and forming part

of the circuit through said plug, a gap being formed in said circuit, a solid body of arc preventing high resistance material in said gap to prevent the passage of any currents but those of high potential, and means for preventing lateral displacement of said high resistance body.

5. In a spark plug, an insulating block, a conductor carried thereby, a binding post 10 resting directly on the end of said block and separated from the end of said conductor by a space, means in said space for interposing a uniform resistance in the circuit to said conductor, and an independent cap for 15 securing said binding post to one end of said block.

6. In a spark plug an insulating block, a conductor carried thereby, a binding post independent of said conductor and having an 20 enlarged head resting on the face of one end of said block, and a cap independent of said binding post for clamping the latter to said insulating block, said binding post and cap being provided with complementary means 25 for preventing relative rotation.

7. In a spark plug an insulating block, a conductor carried thereby, a binding post independent of said conductor having an enlarged head resting on the face of one end 30 of said block, independent means for clamping the enlarged portion of said binding post to said block, and means for preventing relative rotary movement of said binding post and said insulating block.

8. In a spark plug an insulating block, a conductor carried thereby, a binding post having an enlarged head resting on one end of said block, said head being provided with a cavity in its under face coöperating with 40 the end of the block to form a closed chamber, means in said chamber for interposing a uniform resistance in the circuit to said conductor, and means for securing said binding post in position.

45 9. In a spark plug, an insulating block, a conductor carried thereby, a binding post in circuit with said conductor and having an enlarged head resting on one end of said block, and a cap fitting over said head 50 and secured to said block.

10. In a spark plug, an insulating block, a conductor carried thereby, a binding post in circuit with said conductor and having an enlarged head resting on one end of 55 said block, a cap fitting over said head and secured to said block, and means for preventing rotation of said binding post with relation to said cap.

11. In a spark plug, an insulating block, 60 a conductor carried thereby, a binding post in circuit with said conductor and having an enlarged head resting on one end of said block, said head being provided with an angular portion, and a cap fitting over said 65 head and secured to said block, said cap

being provided with an angular opening conforming to the angular portion of said head.

12. In a spark plug, an insulating block, a conductor carried thereby, a binding post 70 in circuit with said conductor and having an enlarged head resting on one end of said block, said head being provided with an angular portion, the underside of said head being provided with a recess, and a cap 75 fitting over said head and secured to said block, said cap engaging the angular portion of said head.

13. In a spark plug, an insulating block, a conductor carried thereby, a binding post 80 having an enlarged head resting on one end of said block, means for securing said post in position, and a body of material of high resistance interposed between said head and the contiguous end of said conductor.

85 14. In a spark plug, an insulating block, a conductor carried thereby, a binding post in circuit with said conductor and having an enlarged head resting on one end of said block, said head being provided with a cavity, means for securing said binding post in position, and a body of material of high resistance located in said cavity.

90 15. In a spark plug, an insulating block, a conductor carried thereby and having one terminal flush with said block, a binding post resting directly on the end of said block adjacent said flush terminal and provided with a chamber over said terminal, 95 and means for securing said binding post in position.

16. In a spark plug, an insulating block, a conductor carried thereby and having one terminal flush with one end of said block, a binding post secured to said block and adjacent said flush terminal, and a body of material of high resistance interposed 105 between said binding post and said flush terminal.

110 17. In a spark plug, an insulating block, a conductor carried thereby and having one terminal flush with one end of said block, a binding post having a head secured to said block adjacent said flush terminal and provided with a cavity in its under face coöperating with the end of the block to form a closed chamber, and means in said chamber for interposing a uniform resistance in the circuit to said conductor.

115 18. A spark plug comprising an insulating block, a conductor carried thereby, packing encircling said block, a supporting bushing forming part of the ground terminal, a bearing cap inclosing said packing and wholly inclosed within said bushing, and a second bushing having one edge fitting within said cap to compress said packing.

120 19. A spark plug comprising an insulating block, a bearing cap surrounding the 130

same and provided with a smooth exterior surface, an annular space being formed between said block and said cap, and packing material forced into said space to frictionally unite said block and cap to form a single unitary device.

20. In a spark plug, an insulating block provided with an annular rib, a bearing cap surrounding said rib and provided with a smooth exterior surface, an annular space being formed between said block and said cap adjacent said rib, and packing material forced into said space to frictionally unite said block and cap to form a single unitary device.

21. In a spark plug, a solid insulating block provided with a longitudinal bore for a portion of its length, and a conductor wire having its sparking terminal projecting from the open end of said bore, the

other end of said conductor being embedded within the solid portion of said block and terminating flush with the outer end face thereof.

22. In a spark plug, an insulating block, 25 a conductor carried thereby, a binding post in circuit with said conductor and having an enlarged angular head supported by one end of said block, and a cap having an angular portion engaging said head, and secured to said block.

In testimony whereof, we have signed this specification in the presence of two subscribing witnesses.
